HEEL FINISHING MACHINE

Antimo Capomacchio and Rudolph Schiavulli,
Providence, R. I.

Application May 26, 1933, Serial No. 673,084

7 Claims. (Cl. 51—102)

Our invention relates generally to shoe manufacture or rebuilding, and particularly to a process and apparatus for scouring and finishing heels, and an important object of our invention is to provide a procedure and an apparatus for carrying out the procedure whereby the rand may be properly separated from the upper of the shoe preparatory to scouring the heel, and for protecting the upper and guiding the heel during the scouring operations.

It is also an important object of our invention to provide a procedure and an apparatus of the type described above whereby the shoe is prepared for the final buffing and the sinking of the mark, accurately and without injury to the upper of the shoe.

Other objects and advantages of our invention, will be apparent from a reading of the following description in connection with the drawings, wherein for purposes of illustration we have shown a preferred embodiment of our invention.

In the drawings:

Figure 1 is a transverse vertical sectional view showing parts in section and parts in elevation of the embodiment showing a shoe applied thereto.

Figure 2 is a transverse vertical sectional view through Figure 1.

Figure 3 is a side elevational view of the grooving or separating tool.

Figure 4 is a side elevational view of the marking tool.

Figure 5 is a sectional view through one of the protector guide rings.

Figure 6 is a sectional view through a portion of one of the circular guard members.

Referring in detail to the drawings, the numeral 5 refers generally to a horizontal bar of a conventional type of shoe scouring machine, and the numeral 6 refers generally to the rotating shaft on which the scouring wheel generally designated 7 is mounted between the lower half 8 and the upper half 9 of the suction hood of the said machine. The grooving tool 10 is fixed to the shaft 6, as is the marking tool 11 in convenient positions with relation to the scouring or buffing wheel 7.

It will be observed that the upper half 9 of the suction hood is hinged on a pin 12 which traverses ears 13, the ears being located outside of the bracket 14 which the pin 12 also traverses, and the bracket 14 is secured by means of a set screw 15 in a desired position on the bar 5. A shoe is generally designated 16, the upper thereof 17 and the heel thereof 18.

In accordance with the invention we mount

on the bar 5 either one or two arms 19. It will usually be convenient to have two of the arms 19, but as they are similar in construction and reversed in position, description of one will suffice to describe the other.

Each of the arms 19 is connected to the bar 5 by means of a yoke 20 clamped by bolts 21. The opposite end of the arm is provided with a U-shaped portion 22 having the arms 23, 24 in each of which is a longitudinal slot 25, 26 through which are arranged bolts 27, 28 which are engaged with a circular guard member generally designated 29 for supporting the guard member in spaced relationship around the rotary shaft 6. The guard 29 comprises the hub portion 30 having on its outer end the narrow flange 31 and at its inner end the flange 32 which is relatively wide and provided at its perimeter with a short grooved lateral flange 33 provided in turn with a radial flange 34 which acts as a shoulder. The groove 35 which is located at one side of the flange 34 is provided to receive a circular spring wire retainer 36 which has radially inwardly directed ends 37 which are entered in radial openings in the groove 35 as shown in Figure 2.

The retainer ring 35 acts in conjunction with the shoulder 34 to confine on the rim of the guard 29 a freely rotatable protector guide ring which is generally designated 38. The protector ring 38 acts as a guide for applying the shoe to the scouring wheel 7 and its cross section is clearly shown in Figure 5. The ring has an annular portion 40 which fits between the retainer ring 35 and the shoulder 34 of the guard member so that it is retained against axial movement on the guard member but permitted free rotation relative to the guard member. The groove portion 41 rides on the shoulder 34 of the guard member. The inward face of the ring 38 is beveled as indicated at 42 in order to maintain this portion of the ring out of contact with the buffer or scouring wheel 7 while permitting the radially outward extremity of the rings 38 to closely approach the sides of the scouring or buffer wheel 7 as shown in Figure 1.

The outer side of the ring 38 is rounded gently as indicated at 43 for contacting with the upper of the shoe, while the radially outward extremity 44 is rounded, and pointed in order to enter the groove provided by the tool 10 between the heel and the upper, so as to correctly position the shoe relative to the scouring wheel 7.

The scouring wheel 7 comprises a pair of spaced disks 45, 46 having hubs 47, 48 whose

meeting ends are stagger cut as indicated at 48 so that the hubs when engaged are locked against relative rotation. The hubs are locked in position on the shaft 6 for rotation therewith by means of individual set screws 50, 51. It will be observed that the guard 28, by virtue of the arrangement of the arms 19 which are connected to the flange 31 of the guard hub 30, is positioned concentrically spaced from the shaft 6, with the large flange portion 32 axially spaced from the side of the buffer wheel so as to avoid contacting the buffer wheel. It will also be observed that the lateral flanges 33 of the guard members overhang the peripheral edges of the buffer wheel flanges 45, 46 and that the inward side of the said flanges 33 are radially outwardly spaced from the periphery of the said portions 45, 46 so as to clear the same. The clearance provided by the beveling 42 of the guide rings 38 between the 10 guide rings and the buffer annulus 52 of the buffer wheel 1 has already been alluded to. It will also be observed that the pointed extremity 44 of the guide ring leans toward and closely approaches the periphery of the buffer element 52 at 15 one side thereof so as to give the shoe heel the correct relationship to the buffer element during the scouring or buffing operation.

Between the flanges 45, 46 is arranged a wooden or other suitable block 53 which is held in place by means of pins 54, and the block 53 carries the felt buffer element 52 carrying the sand paper or similar work face 52'. The flanges 45, 46 may be separated for removal and replacing of the buffer element.

The procedure of the invention comprises applying the shoe to the tool 10 which is a sleeve 55 secured by means of a set screw 56 to the shaft 6 and having a portion of increased diameter 57 between which and the sleeve portion 55 is located in a beveled groove forming annulus 58 which has a wide side 59 and a narrow side 60. The annular portion 58, the tool being rotating, is applied between the upper and the heel or rand of the shoe so as to separate the same and open the rand channel for reception of the rounded pointed extremity 44 on the guide rings 38 and facilitate buffing of the heel. The shoe is then applied to the scouring wheel in the manner shown in Figure 1, wherein the shoe, while being maintained against the guide ring may, by virtue of the freely rotatable mounting of the guide ring, be rotated into any desired position required or desired for the proper buffing or scouring operations. It will be observed that the presence of the guide ring 38 not only protects the upper against coming into contact with the buffer wheel, but also makes movement of the shoe and the heel in an axial direction impossible as long as the shoe is kept in proper position by the operator. This produces absolutely accurate finishing of the heel and facilitates and quickens the buffing or scouring of the heel, while absolutely protecting the upper against injury by coming into contact with the buffer wheel. The tool 10 is also used to separate the vamp and the welt so as to facilitate stitching on of the sole of the shoe. In applying the tool 10, the portion 51 is applied against the edge of the sole so that the portion 58 is prevented from cutting the welt stitches. The portion 55 is made smaller in diameter than the portion 57 so as to clear the shoe upper while working on the sole.

After the formation or restoration of the groove or rand channel of the shoe by the tool 75 10 and the completion of the buffing or scouring

operation in which the buffer wheel 1 is concerned, the shoe is removed and applied to the marking tool 11. The marking tool 11 comprises the sleeve 61 connected by means of a set screw 62 to the shaft 6, the sleeve having at one end the flanged annular member 63 which has a slight concavity at the point 65 for rounding and smoothing the rand and outwardly of this is a relatively small beveled annulus 66 which is arranged to enter the rand channel between the heel and the upper or rand for smoothing and shaping the channel. The shoulder or rib 64 defined by the concavity 65 and a portion 67 of relatively greater diameter does the marking of the heel. A portion of the concavity 65 burnishes a portion of the heel between the rand channel and the mark which the shoulder 64 makes thereon. It will be observed that the preparation of the shoe by the use of the tool 10 for opening the rand channel of the shoe, enables the tool, 11 to properly finish and mark the heel accurately and neatly and without the slightest chance of injuring either the heel or the upper under ordinary circumstances.

It will be observed that the result of the invention considered in the aspect of an apparatus and in the aspect of a procedure, is accurate finishing and marking of shoe heels and soles in a shorter time than has heretofore been adequate for proper and accurate work; and the establishment of the practical possibility of achieving such excellent work with comparatively unskilled operators; and the assurance in shoe factories of the perfection of the scouring and finishing up operations, thereby materially reducing expensive accidents to the work and generally raising the standard of manufacture, while reducing the expense thereof by eliminating waste and reducing the time required for the operation.

Although we have shown and described here- 40 in preferred embodiments of our invention, it is to be definitely understood that we do not desire to limit the application of the invention thereto, and any change or changes may be made in materials, and in structure and arrangement of 45 parts, as well as in the sequence of duration of steps and operations involved in the process or procedure, when in the spirit of the invention and the scope of the subjoined claims.

Having thus described our invention, what we 50 claim as new is:

1. In a shoe heel finishing machine, a rotatable shaft having a buffer wheel fixed thereto, a stationary guard member surrounding a portion of said shaft with respect to which the said 55 portion of the shaft is free to rotate, an annular guide rotatably mounted on and supported solely by said guard member and having a portion lying closely spaced from one side of the periphery of said buffer wheel.

2. In a shoe heel finishing machine, a rotatable shaft having a buffer wheel fixed thereto, a stationary guard member surrounding and spaced from a portion of said shaft at one side of said buffer wheel, an annular guide rotatably mounted on and supported solely by said guard member and having a portion lying closely spaced from the side and the periphery of said buffer wheel, the periphery of said guard member having a shoulder at its axially inward side and means 65 spaced axially outwardly therefrom and defining a groove in which a portion of said annular guide works, whereby said annular guide is positively prevented from contacting the side and periphery of the buffer wheel.

3. In a heel finishing machine including a rotary shaft having a buffer wheel fixed thereon, a heel guard having a part stationarily supported free of said shaft and in concentric relation to one side of said buffer wheel, said part including an annular rim having a radial shoulder, a guard ring rotatably mounted on said rim in closely spaced relation to the side and periphery of said buffer wheel and engaging said radial shoulder, said shoulder positively preventing engagement of said buffer wheel with said guard ring during the operation of the buffer wheel.
4. In a heel finishing machine including a rotary buffer wheel, a heel guard supported at one side of said buffer wheel, said heel guard including a relatively stationary annulus concentric with said buffer wheel, said annulus being formed with a radial shoulder at the inner side of its periphery, and a guard ring rotatably mounted on the periphery of said annulus and rotatably engaging said shoulder and closely approaching the adjacent side and the periphery of the buffer wheel, said shoulder acting to positively prevent engagement of said guard ring with the side and the periphery of said buffer wheel, the axially inward side of said guard ring being angulated in a radially inward direction away from the side of the buffer wheel.
5. In a heel finishing machine including a rotary buffer wheel, a heel guard supported at one side of said buffer wheel, said heel guard including a relatively stationary annulus concentric with said buffer wheel, said annulus being formed with a radial shoulder at the inner side of its periphery, and a guard ring rotatably mounted on the periphery of said annulus and rotatably engaging said shoulder and closely approaching the adjacent side and the periphery of the buffer wheel.
6. In a heel finishing machine including a rotary shaft having a buffer wheel fixed thereon and a suction hood enclosing the buffer wheel, a side of said suction hood being with an opening through which said shaft passes, an annulus supported around said shaft and close to a side of said buffer wheel, a tubular part extending from said annulus and surrounding said shaft between said annulus and said side of the suction hood and received by and closing said opening in the side of the hood, whereby loss of effective suction from said hood is prevented.
7. In a heel finishing machine including a rotary shaft having a buffer wheel fixed thereon and a suction hood enclosing the buffer wheel, a side of said suction hood being formed with an opening through which said shaft passes, an annulus supported around said shaft and close to a side of said buffer wheel, a tubular part extending from said annulus and surrounding said shaft between said annulus and said side of the suction hood and received by and closing said opening in the side of the hood, whereby loss of effective suction from said hood is prevented, and a heel guard rotatably mounted on said annulus and concentric with said buffer wheel.

ANTIMO CAPOMACCHIO.
